United States Patent Office

Des. 194,309
Patented Jan. 1, 1963

194,309

SHOE

Beth Levine, 59 W. 12th St., New York, N.Y.

Filed Aug. 16, 1962, Ser. No. 71,309

Term of patent 14 years

(Cl. D7—7)

FIG. 1

FIG. 2

FIG. 3

FIG. 4

FIG. 5

I claim:

The ornamental design for a shoe, substantially as shown.
